ENGINE STARTER

James E. Buxton, Elmira, N. Y., assignor to
 Bendix Aviation Corporation, Elmira Heights,
 N. Y., a corporation of Delaware

Application December 21, 1945, Serial No. 636,373

5 Claims. (Cl. 74—7)

1

The present invention relates to an engine starter and more particularly to that type of starter in which the mechanism remains operatively connected to the engine to be started until said engine is properly self-operative.

It is an object of the present invention to provide a novel engine starter of the above type which is simple and economical in construction and easy to assemble.

It is a further object to provide such a device in which the friction between the actuating and control members for the engine driving member is increased through the action of centrifugal force to resist the disengaging movement of the engine driving member when momentary or isolated impulses are received from the engine during cranking.

It is a further object to provide such a device in which a ring of material having a high coefficient of friction is placed between the actuating and control members in position to engage and frictionally clutch said members together when the control member is misaligned by centrifugal force.

It is a further object to provide such a device wherein the control member is provided with means for cocking or moving it out of alignment on the actuating member responsive to centrifugal force to thereby cause the control member to bind frictionally on the actuating member.

Further objects and advantages will be apparent to those skilled in the art from the following description and accompanying drawing, in which:

Fig. 1 is a side elevation partly in section of a preferred form of the present invention shown in idle position;

Fig. 2 is a view similar to Fig. 1 showing the starter drive in overrunning position;

Fig. 3 is a detail view in perspective of the actuating member of the starter, with the anti-drift means partly broken away;

Fig. 4 is a side elevation partly in section of a form of the actuating member embodying a friction ring; and

Fig. 5 is a perspective view of the casing and clutch housing members showing the method of assembly.

In Fig. 1 of the drawing, there is illustrated a power shaft 1, which may be the armature shaft of an electric motor, not shown, having a smooth reduced extension 1' providing a stop shoulder 2 against which thrust washers 2' are seated. An actuating member in the form of a screw shaft 3 is fixed thereon in any suitable manner as by means of the drive pin 4 extending through the

2

power shaft, and retained therein by suitable means such as a set screw 4'. A control member in the form of a nut 5 is threaded on the screw shaft 3. An engine driving member in the form of a pinion 6 is slidably journaled on the reduced portion 1' of the power shaft 1 in position to engage and rotate an engine member such as a gear 7 when the pinion is pressed into cranking position against stop shoulder 2. A yielding driving connection between the control nut and pinion is provided comprising a yielding member in the form of a sleeve 8 of elastically deformable material such as rubber seated on the control nut 5 against a flange 9, and a normally engaged overrunning clutch comprising a driving clutch plate 11 having "saw-tooth" dentals 12 and a driven clutch plate 13 having similar dentals 14. Driving plate 11 is demountably attached to a barrel or casing member 15 by means of integral lugs 16 fitted within longitudinal slots 17 in the barrel and held therein by a combination lock member and clutch housing member 18. The driven plate 13 is fixed in any suitable manner such as welding at 19 to the pinion 6 and is held in contact with the driving plate 11 by a spring 21 seated at one end against a shoulder 22 on the periphery of plate 13 and bearing at the other end against the radial flange 23 of clutch housing 18. The rear of barrel 15 is formed with an inwardly extending rib 24 against which the flange 9 of the control nut 5 rests with a slight pressure imparted thereto by the initial compression of rubber sleeve 8.

According to the present invention, means are provided for inclining or misaligning the control nut 5 on the screw shaft 3 responsive to centrifugal force so as to cause the control nut to bind frictionally on the screw shaft and thereby resist traversal thereon when the parts are rotating at high speed. For this purpose, suitable clearance is provided between the threads 27 and 28 on the nut and screw shaft respectively, the nut is counterbored at its rear end as shown at 25, and an eccentric mass 26 is formed thereon. The thread clearance is so chosen in conjunction with the length of the threads 27 as to permit substantial misalignment of the parts so as to cause a progressive increase in the inter-thread friction as the rotative speed of the control nut 5 increases at the moment when the engine fires.

Anti-drift means for the pinion 6 while in idle position are provided in the form of a pin 29 held within a radial hole 30 in the eccentric portion 26 of control nut 5. The anti-drift pin 29 is pressed into a recess 31 in the screw shaft 3 by

a spring 32, the upper end of said spring being seated against a ring 33 which is pressed on the control nut 5 in position to cover the hole 30 and is provided with an opening 34 forming a guide for the pin 29. The location of the anti-drift pin in the eccentric portion of nut 5 causes the pressure of the pin on the screw shaft to assist the action of the eccentric mass in causing the cocking action of the nut on the screw shaft.

In the operation of this embodiment of the invention, rotation of the power shaft 1 and screw shaft 3 causes the control nut 5 and its associated parts to traverse to the right in Fig. 1 pushing the pinion 6 into mesh with the engine gear 7 and upon contact of the pinion against thrust washers 2' to close the clutch 11, 13. Further traversal of the control nut 5 compresses the rubber sleeve 8 until sufficient torque is transmitted to the engine gear 7 to cause it to rotate and crank the engine. When the engine fires, the sudden acceleration of the engine gear is multiplied by the gear ratio of the gear and pinion and transmitted through the closed clutch 11, 13 to the control nut 5, causing it to overrun and move backward on the screw shaft 3 thus relaxing the rubber sleeve 8 and allowing the clutch 11, 13 to overrun. The high speed of rotation of the control nut at this time causes the eccentric mass 26 thereon to cock the nut on the screw shaft thus causing the nut to bind and resist traversal back to idle position in a manner similar to the action of the pinion 6 on its screw shaft 4 as shown and described in the patent to Bendix, 1,274,369. The screw shaft is also rapidly accelerated by the release of the cranking load, whereby the nut remains clutched to the screw shaft by the cocking action of the eccentric mass as long as the operator maintains the starting switch closed, and the pinion is consequently held in mesh with the engine gear.

If the engine should fail to continue self-operative, the engine gear slows down, retarding the pinion 6 and its clutch member 13. When the latter slows down to the speed of the clutch member 11, the saw-tooth dents of the clutch members engage under the action of the spring 21, whereby the nut 5 is also retarded and consequently traversed by the screw shaft to the right in Fig. 1, and cranking is resumed. The engine is thus cranked continuously until it is reliably self-operative. When the engine is properly functioning, the operator deenergizes the starting motor whereupon the armature shaft 1 and screw shaft 3 come to rest. The control nut simultaneously slows down until the cocking effect of the eccentric mass 26 is reduced to the point where the torque transmitted from the pinion through the overrunning clutch 11, 13 is sufficient to move the nut back to idle position, thus drawing the pinion out of mesh with the engine gear. Thereafter the parts are yieldably maintained in idle position by the engagement of anti-drift pin 29 in recess 31 in the screw shaft.

In Fig. 4 of the drawing, a second embodiment of the present invention is shown in which the inter-thread friction between the control nut 5' and screw shaft 3 is either augmented or supplanted by a friction ring 35 having a high coefficient of friction interposed between said nut and shaft. The ring 35 may have any suitable location between the nut 5' and shaft 3 but is preferably pressed into the bore at the forward end of the control nut and held therein in any desired manner as by friction. The inner diameter of the ring 35 is radially spaced from shaft

3 while in idle position. The operation of this form of the invention is similar to that of the first embodiment except that when centrifugal force produces misalignment of the nut 5', on the shaft 3, the ring 35 is caused to engage and bind frictionally on the tops of the threads of the screw shaft. The ring 35 is preferably formed of a material such as rubber, fiber or plastic having a high coefficient of friction whereby the frictional connection thus established between nut 5' and shaft 3 is effective in retarding relative motion therebetween.

Although certain embodiments of the invention have been shown and described in detail, it will be understood that other embodiments are possible and changes may be made in the form and arrangement of the parts without departing from the spirit of the invention as defined in the claims appended hereto.

What is claimed is:

1. In an engine starter, the combination of a power shaft, an actuating member fixed thereon, a control member having an inclined connection to said actuating member, said connection having means for permitting relative misalignment between said members, an engine driving member slidably journaled on said power shaft for engagement with and rotation of a member of an engine to be started, means for driving said engine driving member from said control member, said means including an over-running clutch; and speed responsive means including a dynamically unbalanced mass on said control member for increasing the friction between said control member and actuating member by misalignment thereof.

2. In an engine starter, the combination of a power shaft, a screw shaft fixed thereon, a control nut having a female thread for a portion of its length mounted on said screw shaft with sufficient clearance to permit relative inclination of the respective axes of rotation thereof, an engine driving member slidably journaled on said power shaft for movement into and out of driving engagement with a member of an engine to be started, means for traversing and rotating said engine driving member from said control nut, said means including an overrunning clutch; and means on said control nut responsive to centrifugal force for inclining said nut on said shaft and thereby increasing the friction therebetween to resist disengagement of said engine driving member from the engine member.

3. In an engine starter, the combination of a power shaft, a screw shaft fixed thereon, a control nut loosely threaded on said screw shaft and provided with a counterbore for a substantial part of its length to permit said nut to tilt out of the axis of rotation of said shaft, an engine driving member slidably journaled on said power shaft for engagement with and rotation of a member of an engine to be started, means including a clutch for driving said engine driving member from said control nut, and means including a centrifugally unbalanced mass on said control nut for causing the axis of the nut to tilt and thereby increase the inter-thread friction between said nut and shaft during the disengaging movement of said engine driving member.

4. In an engine starter, a motor shaft, a screw shaft fixed thereon, a control nut threaded for a portion of its length on said screw shaft with sufficient clearance to permit substantial misalignment of the nut thereon to thereby cause the nut to bind frictionally on the screw shaft, means on

5

said control nut including an anti-drift member acting on said screw shaft for producing said misalignment, a pinion slidably journalled on said motor shaft for movement into mesh with and rotation of an engine gear, and means including an overrunning clutch and a yieldable member for driving said pinion from said control nut.

5. In an engine starter, the combination of a power shaft, a screw shaft fixed thereon, a control nut having a substantial counterbore at its rear end and loosely threaded on said screw shaft to permit relative inclination thereon, a pinion

6

slidably journalled on said power shaft for engagement with and rotation of an engine gear, means including an overrunning clutch for driving the pinion from the control nut, a member having a high coefficient of friction located between said nut and screw shaft in position to establish a frictional connection therebetween when the nut is inclined on the screw shaft, and a centrifugally responsive mass on said control nut for causing inclination of the nut responsive to high speed rotation thereof.
